(57) **CLAIM**

We claim the ornamental design for a 4 button fob transmitter, substantially as shown and described.

DESCRIPTION

FIG. 1 is a front perspective view of the 4-button key fob transmitter of the present invention.

FIG. 2 is a rear perspective of the key fob.

FIG. 3 is a front elevation view of the key fob.

FIG. 4 is a rear elevation view of the key fob.

FIG. 5 is a right side elevation view of the key fob.

FIG. 6 is a left side elevation view of the key fob.

FIG. 7 is a top plan view of the key fob; and,

FIG. 8 is a bottom plan view of the key fob.

Figures show the key fob with structure shown in broken lines that are not a part of the claimed invention.
